UNITED STATES PATENT OFFICE.

KENT A. HAWLEY, OF BALTIMORE, MARYLAND, ASSIGNOR TO LOCKE INSULATOR CORPORATION, OF BALTIMORE, MARYLAND, A CORPORATION OF MARYLAND.

INSULATOR.

Application filed September 22, 1925. Serial No. 57,931.

This invention relates to insulators.

The object of the invention, generally stated, is to provide a protective device in the nature of a guard or shield located beneath or at the open bottom of an insulator for excluding dust and particles of matter which might otherwise accumulate on the underside of the insulator and which, if of a more or less conducting nature, might cause short circuiting or at least a sufficient shortening of the leakage path as to result in decreased efficiency if not destruction of the insulator.

It has been proposed to provide a cup-like member beneath an insulator to exclude foreign matter, the cup member being attached to a suspension element, supporting pin or the like, depending upon the type of insulator, but such tentative arrangements have been found unsatisfactory in actual service, partly because of the fact that the shield or protector is really separate from the insulator itself.

The object of the present invention, more specifically stated, is to provide an insulator with a protective shield carried thereby and secured thereto so that no reliance will be placed upon attachment to a pin or the like, it being consequently possible to equip the insulators with the protective shields or guards at the factory and prior to shipment so that the user may mount the insulator in the usual manner without any preliminary operation such as would be entailed by installing the protecting devices.

Still another object of the invention is to provide an insulator and a shield or guard therefor connected therewith in an extremely simple manner, it being possible to effect disconnection in case any necessity might arise.

A further object of the invention is to provide a shield or guard which may be constructed as a stamping from thin sheet metal having sufficient resilience that the guard may be snapped into place as for instance by the coaction of interfitting ribs, grooves or the like, the resilience serving to retain the guard in place, the guard being more over of such formation as to avoid contact or interference with the supporting pin, suspension element or the like used in conjunction with the insulator.

To the attainment of the foregoing and other objects and advantages, the invention

consists in the details of construction and the arrangement and combination to be herein-after more fully described and claimed, and illustrated in the accompanying drawing in which:

The figure is a view partly in elevation and partly in section of an insulator and guard constructed in accordance with the invention.

Referring more particularly to the drawing, I have, for the sake of illustration, shown an insulator 1 of the pin type though it should be distinctly understood that there is no limitation in this respect inasmuch as the invention is equally capable of employment in connection with certain other types as will of course be apparent to one skilled in the art as the description progresses. The insulator 1 is of course formed as a body of insulating material and is here represented as having a transverse groove 2 in its top and an annular groove 3 in its periphery, as is customary. The bottom portion of the body is formed with outer and inner depending skirts 4 and 5 respectively, here represented, though not necessarily, as being of unequal lengths. The skirts are spaced apart and inwardly of the inner one is a socket 6 which receives the supporting pin 7 which may be of any ordinary or preferred type and which may be secured in place within the socket by any suitable means or method.

When insulators of this variety, or other types for that matter, are used in quarries, around cement mills and many other places where there is a great quantity of dust in the air, it frequently occurs that the under-surface or the walls of the skirts become coated with fine particles which in many instances are sufficiently conductive to reduce the current leakage path of the insulator so that its efficiency is seriously impaired, short circuiting and flash-overs often resulting.

To avoid this condition I provide a shield or guard indicated generally by the numeral 8, which guard is preferably constructed of thin sheet metal pressed, stamped or otherwise formed into a cylindrical shell having an upstanding outer wall 9 of practically the same diameter as the inside of the outer skirt 4. At the center of the guard or shell is an opening 10 for the accommodation of the pin 7, the material around the opening being formed into a tubular sleeve 11 which

is spaced somewhat from the pin as contact therewith would be undesirable. The diameter of the sleeve portion 11, while greater than that of the pin is less than that of the 5 inside of the inner skirt 5 so that in actual practice the sleeve portion will be located intermediate the pin and the inner skirt but spaced from both. It is also preferable, though not necessary, that the sleeve portion 10 11 have a greater height than the outer wall 9 so as to extend an appreciable distance upwardly beyond the lower edge of the inner skirt, as clearly indicated.

For effecting connection of the guard or 15 shield with the insulator. I have found it a convenient arrangement to form the wall 9 with an outwardly pressed rib or projection 12 and to form the inner wall of the outer skirt 4 with a corresponding groove 20 or depression 13 receiving the rib. The rib and groove need not be continuous as it is obvious that a plurality of projections and corresponding recesses might be provided at intervals, such variations being immaterial. If necessary, the wall 9 may be slit 25 at spaced points to facilitate the engagement of the rib or ribs within the groove or grooves, as the case may be. These and other variations fall within the spirit of the 30 invention.

In the use of an insulator equipped with the guard, it is quite clear that it will be impossible for any great amount of dust or pulverized matter to gain access to and form 35 a coating on the underside of the insulator or the walls of the skirts thereof, the object of the invention thereby being most effectively achieved. It is quite apparent that assembly may be effected at the factory and 40 the complete insulators packed and shipped in condition ready for use though it is likewise clear that if preferred the insulators might be sold separately and the guards or shields subsequently applied when conditions 45 might require their employment, the mode of attachment of the guards being such that assembling may be effected without the employment of any special tools and without requiring any great degree of skill. Obviously accidental disengagement of the 50 shields or guards can not occur owing to the engagement of the rib or ribs within the groove or grooves provided for their reception.

While I have shown and described the preferred embodiments of the invention, it should be understood that the same is merely 55 illustrative as the right is reserved to make all such changes in the form, details of construction, mode of manufacture and the like

as will not depart from the spirit of the invention or the scope of the claims hereunto appended.

Having thus described the invention, I 60 claim:

1. In combination with an insulator of the pin type having outer and inner skirt portions, a protective guard of metal including a bottom portion, an upstanding outer side wall and a central upstanding sleeve portion, said outer wall portion of the guard being detachably engaged with and lying against the inner periphery of the outer skirt portion of the insulator, said bottom portion defining a substantial closure for the 70 bottom of the insulator, and said upstanding sleeve portion being located within the confines of the inner skirt portion in spaced relation thereto and to the pin.

2. In combination with an insulator of the pin type having outer and inner skirt portions, a protective guard of metal including a bottom portion, an upstanding outer side wall and a central upstanding sleeve portion, said outer wall portion of the guard 80 being detachably engaged with and lying against the inner periphery of the outer skirt portion of the insulator, said bottom portion defining a substantial closure for the bottom of the insulator, said upstanding 85 sleeve portion being located within the confines of the inner skirt portion in spaced relation thereto and to the pin, said outer wall portion extending to a point beyond the lower edge of the inner skirt portion of the 90 insulator, and said sleeve portion extending upwardly beyond the lower edge of the inner skirt portion.

3. In combination with an insulator of the pin type having outer and inner skirt portions, a protective guard of metal including a bottom portion, an upstanding outer side wall and a central upstanding sleeve portion, said outer wall portion of the guard being detachably engaged with and lying 100 against the inner periphery of the outer skirt portion of the insulator, said bottom portion defining a substantial closure for the bottom of the insulator, and said upstanding sleeve portion being located within the confines of the inner skirt portion in spaced relation thereto and to the pin, said outer skirt portion having its inner periphery formed with a single continuous groove and the outer wall portion of the guard having 105 an outwardly pressed rib frictionally engaged within said groove.

In testimony whereof I affix my signature.

KENT A. HAWLEY.
